STANLEY PIVONSKI, OF COLGATE, AND FREDERICK JOSEPH CANITZ, JR., OF BALTIMORE, MARYLAND, ASSIGNEES TO ANCHOR POST FENCE COMPANY, OF JERSEY CITY, NEW JERSEY, A CORPORATION OF NEW JERSEY

MEANS FOR FASTENING WIRE FABRICS TO FENCE OR GATE POSTS AND THE LIKE

Application filed February 14, 1929. Serial No. 339,898.

This invention relates to devices for fastening, under tension, wire fabric, especially of the woven chain-link type, to fence or gate posts, bars or similar supporting structures; our object being to provide a simple and inexpensive construction whereby the effective and reliable attachment of the margin of the fabric to the adjacent supporting structure can be easily and rapidly attained.

10 The invention in the form or forms herein illustrated embodies the combination with a hollow supporting structure, wire fabric having a margin thereof arranged adjacent to and parallel with said structure, and a 15 stretcher bar interlocked with the said margin longitudinally thereof, of a fastening and tensioning device between the stretcher bar and the supporting structure comprising a shank having a hook portion in engagement with the stretcher bar, and a threaded portion in co operative engagement with a nut element having a head and a bifurcated body which latter is seated in an aperture in the adjacent wall of the structure and is locked 20 in place against withdrawal without restraining it against rotation by the expansive or spreading action of the shanks on the internal walls of said body when the element is manipulated. The head of the nut element 25 bears against the opposing outer face of the supporting structure, and is readily manipulative by means of a suitable tool to adjust the shank and the stretcher bar in respect to the structure and thereby effect the requisite tensioning of the fabric.

30 The invention also comprises features of construction and combination of parts which will be hereinafter described, and the scope of the invention then defined in the appended 35 claims.

In the drawings—

Figure 1 is a side elevation of a fragment of wire fabric and a part of a hollow post, or 45 the like, to which the fabric is secured by a device embodying a form of our invention, the post being shown partly in section to expose the expansive nut element on the connecting shank of the device.

50 Fig. 2 is a sectional plan of the post showing

the fastening device and the stretcher bar for the wire fabric.

Fig. 3 is a transverse vertical section of the post, as on the line 3—3 of Fig. 2.

Fig. 4 is a section of one wall of the post, 55 an expandible nut element, and the threaded end of a connecting member, said nut element being shown in contracted condition preparatory to its entry in an aperture of the wall.

Fig. 5 is a sectional view showing the elements as assembled and locked to the post.

Fig. 6 is a perspective view of the expandible nut element.

Figs. 7 and 8 are sectional views showing a modified form of the nut element as inserted 65 in the apertured post, respectively before and after the interlocking engagement of the threaded shank with said element.

Fig. 9 is a transverse section through the modified nut element and the shank, as on the 70 line 9—9 of Fig. 8.

Referring to the drawings, 10 designates a portion of a hollow or tubular support of generally rectangular cross-section, which support may, for example, constitute a post 75 for a woven wire fence, or one of the members of a gate frame wherein woven wire fabric is supported. A fragment of wire fabric 11 of the so-called chain-link type is illustrated as fastened to the support.

80 12 designates a stretcher bar extending through the marginal links of the fabric adjacent to and parallel with the support 10; and 13 designates one of a series of fasteners which are located at intervals along the support and are engaged with the bar 12 in a manner to maintain it parallel to the support and hold the fabric under constant tension.

85 The fastener, in the form illustrated in Figs. 1 to 6 inclusive, comprises a metal rod 90 or shank having a threaded portion 14 extending a suitable distance from one end and having at its opposite end a hook 15. The threaded end of the shank is adapted to be screwed into a nut-like element comprising a 95 head 16 having a longitudinally-divided tapering body whereof the members 17 are bored and internally threaded co-axially with the head and are contractible and expandible with respect to the longitudinal axis 100

of the nut element and are of a greater length than the thickness of the wall of the support so that when the divided members 17 are spread as shown in Fig. 5, the greatest dimension of said spread members is considerably greater than the opening in which they are seated.

When the divided tapering body is contracted to substantially cylindrical form, the longitudinal bore thereof tapers from the inner to the outer end of the body, as illustrated in Fig. 4. Hence the cylindrical body can be easily inserted in an appropriate aperture 18 in the inner wall of the hollow support 10 until the head 16 bears against the wall, whereupon, if the threaded portion of the shank be screwed into and through the head of the nut element, such portion will engage the converging internally threaded portions 19 of the members and will forcibly spread the latter until the threaded surfaces are parallel, or substantially so, thus causing the exterior portions of such member to resume their tapering or substantially conical form and bear hard against the wall of the aperture. Consequently the nut is effectually locked to the support against longitudinal movement but is free to rotate, as illustrated in Figs. 1 and 5. The hook 15 of the shank is engaged with the bar 12 and the head of the nut is manipulated by means of a wrench, or other tool, in a manner to position the shank and the bar with respect to the support to effect the desired tension of the wire fabric.

By a reverse rotation of the nut head, the shank can be moved outward to relieve the tension from the fabric or to release the hook from the stretcher bar, as occasion may require.

The foregoing described construction embodying our invention affords a simple, neat and efficient means for fastening wire fabric to hollow posts and the like, which means avoids the otherwise necessity of extending the shank member entirely through the opposite walls of the post and providing a securing nut on the threaded extremity of the shank.

In Figs. 7, 8, and 9 we have shown a modification of the nut element wherein the bifurcated body 17 is normally cylindrical, or substantially so, and the axial bore thereof is tapering. The inner or larger end of this bore is a trifle smaller in diameter than the bore of the nut element, and the walls of the respective bores are smooth or untapped. The nut element is composed of a metal or alloy relatively softer than that of the threaded shank 14, and the diameter of the cylindrical body is such that it can be readily inserted in the aperture 18 of the support 10. When the body is seated in the aperture the threaded end of the shank is inserted in the bore of the head 16, and the shank is ham-

mered inward to force the threaded shank through the tapering bore of the body. The entering action of the shank upon the tapering body wedges the members 17 apart and jams them against the walls of the aperture, thus preventing withdrawal of the nut element while permitting rotation thereof. The wedging action of the threaded shank on the opposing walls of the members 17 produces a partial thread in the latter, so that when the nut element is turned with a wrench, or other suitable tool, the connecting shank or bolt can be adjusted in either longitudinal direction, as desired, to effect the requisite tensioning of the fabric.

We claim—

1. A tensioning device for a flexible fence or the like, comprising a rod having a thread on one end and means on the other end for securing it to the fence to be tensioned, a nut-like element arranged to be passed through an opening in a support to extend beyond the opposite face of the support from the side thereof adjacent the fence to be tensioned, coacting means on the rod and the inserted end of the nut for expanding that portion of the nut passed through the support to prevent the withdrawal of the nut when the nut is turned to tension the fence.

2. A tensioning device for a flexible fence or the like, comprising a rod having a thread on one end and means on the other end for securing it to the fence to be tensioned, a threaded nut arranged to be passed through an opening in a support to extend beyond the opposite face of the support from the side thereof adjacent the fence to be tensioned, coacting means on the rod and the inserted end of the nut for expanding that portion of the nut passed through the support to prevent the withdrawal of the nut when the nut is turned to tension the fence.

3. A tensioning device for a flexible fence fabric or the like, comprising a rod threaded at one end and having means on the other end for securing it to the fence fabric, a nut-like element having a head and divided members extending from one end of the head, the thickness of said members being greater remote from the head than at their junctions with the head and arranged to be applied head first on the threaded end of the rod, a support having a wall of less thickness than the length of the divided members of the nut and having an opening through its wall, the opening being of greater area than the greatest cross-sectional area of the divided members, so as to permit the free insertion thereof, and coacting means on the rod and nut for spreading the free ends of the divided members beyond the edges of the opening, whereby the nut may be turned to tension the fence and be restrained against longitudinal movement relative to the support.

4. A tensioning device arranged to be con-

5 nected to a support having an opening there-
through, embodying a threaded rod and a nut
comprising a head and a body having divided
members extending from one end of the head,
said body being of greater length than the
thickness of the wall of the support through
which it extends, the cross-sectional area of
10 said members being greater remote from the
head than adjacent to the head but less than
the area of the opening, and coacting means
15 on the nut and rod for spreading the extremi-
ties of said members beyond the edge of the
opening, whereby the nut may be turned to
apply tension to the rod and be restrained
against longitudinal movement relative to
the support.

20 5. A tensioning device arranged to be con-
nected to a support having an opening there-
through, embodying a threaded rod and a
threaded nut comprising a head and a body
25 having divided tapering members extending
from one end of the head, said body being of
greater length than the thickness of the wall
of the support through which it extends, the
cross-sectional area of said members being
30 greater remote from the head than adjacent
to the head but less than the area of the
opening, and coacting means on the nut and
rod for spreading the extremities of said
members beyond the edge of the opening,
35 whereby the nut may be turned to apply
tension to the rod and be restrained against
longitudinal movement relative to the sup-
port.

40 35 Signed at the city of Baltimore and State
of Maryland this 12th day of February A. D.
1929.
